UNITED STATES PATENT OFFICE.

FERDINAND P. SCHOENHARDT, OF MERIDEN, CONNECTICUT, ASSIGNOR TO EDWARD MILLER & COMPANY, OF MERIDEN, CONNECTICUT, A CORPORATION OF CONNECTICUT.

LIGHTING-FIXTURE.

1,090,795.

Specification of Letters Patent. Patented Mar. 17, 1914.

Application filed November 3, 1913. Serial No. 798,850.

To all whom it may concern:

Be it known that I, FERDINAND P. SCHOENHARDT, a citizen of the United States, residing at Meriden, New Haven county, State of Connecticut, have invented certain new and useful Improvements in Lighting-Fixtures, of which the following is a full, clear, and exact description.

The present invention relates to the type 10 of suspended lighting fixtures wherein translucent surfaces are utilized to reflect light against a wall or ceiling and at the same time itself transmit a diffused glow, the translucent substance being embodied in 15 a bowl or tray shaped structure within and above which the lamp, bulb or other source of light is located. Heretofore devices of this character have been constructed in the main of a single piece of translucent fragile 20 material requiring expensive molding operations, and consequently being expensive to replace in case of breakage.

The device of the present invention aims 25 to provide a suspended fixture of this general character wherein the translucent substance may be arranged and furnished in sections carried by a suitable frame so that in the event of the breakage of one section, the whole structure does not have to be removed.

The present device also provides a structure which is simple in its fundamental characteristics and which may be utilized as a basis for a wide variation of design 35 within the boundaries of the general type employed.

One specific embodiment which my invention may take is illustrated in the accompanying drawings and is described in 40 the following detailed specification taken in connection with said drawings.

In these drawings, Figure 1 is a view in 45 side elevation of a suspended lighting fixture constructed in accordance with the present invention, part only of the suspending chains being shown. Fig. 2 is a transverse vertical section of the fixture shown in Fig. 1, and on an enlarged scale, parts being broken away. Fig. 3 is a fragmentary 50 perspective view of part of the frame, the glass panels being removed. Fig. 4 is a fragmentary view in elevation of the side of the frame taken from the interior of the

fixture. Fig. 5 illustrates an ornamental detail.

The lighting fixture shown in these drawings is in the form of a tray-like receptacle, containing a series of panels at the sides for translucent material, and having a translucent bottom. To this end I provide a frame, preferably of metal, and formed of a horizontal angle ring piece 1 having a horizontal ledge or supporting flange 1^a and forming the base of the frame; a horizontal upper ring 2 and a plurality of vertical strips or bands 3 which may be suitably connected to the horizontal rings as by rivets 3^a and which divide the sides of the frame into a series of panels. The horizontal ledge or shelf 1^a of the bottom ring member is designed to support a translucent surface or surfaces 15 made, for instance, of "art" glass. This bottom may be of a single piece or may be formed of a series of sections seated in a frame of suitable configuration, which frame will rest on the ledge 1^a. Between the vertical strips 3 forming the panels, a series of curved sections 5 of translucent material, as for instance the "art" glass before referred to, are inserted, the lower edges of these sections resting on the upper face of the bottom 15 of the fixture, and their adjacent edges being spaced apart by suitable means, as for instance, by the rivets 3^a. In order to retain these inserted panels in position, the strips 3^a are provided with tongues 4 arranged to be bent over the edges of adjacent panels to lock the same against the inner faces of the frame rings 1 and 2 and against the vertical strips. As 90 panels rest upon the upper face of the bottom and as these panels are themselves held to the frame by the tongues 4, it will be evident that the bottom itself is likewise held in position. These tongues may be 95 formed in any suitable manner, as for instance by a separate piece of flexible metal attached to the inner face of the transverse strips and cut to provide tongues 4-4, as shown clearly in Figs. 3 and 4 of the drawings.

The frame with its translucent panels is intended to be suspended from, and to lie adjacent, the ceiling of the room which it is desired to illuminate. One form of suspension means for the tray is as follows:

At a series of spaced intervals about the edge of the tray, I dispense with the usual rivets 3^a and provide hooked members 6 located on the inner edge of the tray and 5 having threaded shanks 7 which extend through alined bores formed in the ring 2 and strips 3, and are held to the frame by means of ornamental nuts 8 screwing upon the threaded ends of the shanks 7 which 10 project beyond the outer face of the ring 2. The edges of adjacent panels 5 are preferably cut away, as at 5^a, to permit the insertion of the shank 7 of the suspending hooks and also to permit these hooks to be 15 used as a means of clamping brackets 10 to the interior of the frame. These brackets 10 may be of any suitable design, one form being shown in the drawings wherein the bracket is provided with a bore through 20 which the shank of the hook extends, and with a threaded stud 11 at its opposite end to which a fixture carrying an electric bulb may be secured. The frame is, of course, suspended by means of chains 9 whose end 25 links may engage with the hooks 6 carried by the frame.

The panel 15 forming the bottom of the tray may have an exterior ornamental fixture attached thereto, such, for instance, as 30 an ornamental knob 12 having a reduced threaded stem 12^a inserted through an opening formed, say, centrally of the bottom panel 15 and engaged by a nut 13 at the inner side of the tray. A suitable rosette 35 14 may be carried and supported by the knob 12 and rests against the under external face of the panel. This particular attachment, however, forms no part of the present invention and is merely referred to to show 40 one commercial embodiment of the completed article.

It will, of course, be understood that the configuration of the frame work and, therefore, of the tray, may vary widely and that 45 the tray by no means is limited to a circular construction; also that the frame and the panels may be widely varied in design and ornamentation, this last applying also to the minor detail features of ornamental construction. Nor do I wish to be limited to the specific means shown for supporting the 50 tray to the ceiling and for the attachment of the lighting element thereto, as this may vary widely to suit different conditions and 55 designs.

What I claim, therefore, and desire to secure by Letters Patent is:

1. A reflecting lighting fixture of the character described comprising a frame work 60 having an open top and a bottom opening therein and having a plurality of openings in its sides, a covering for said bottom opening, means carried by said frame for supporting said covering, translucent material

carried by said frame work and covering the 65 openings in the sides thereof, and means for retaining said side and bottom covering on said frame.

2. A reflecting lighting fixture of the character described comprising a frame work 70 having an open top and a bottom opening therein and having a plurality of openings in its sides, a covering for said bottom opening including translucent material, means carried by said frame work for engaging 75 and supporting said covering, a plurality of separate panels of translucent material carried by said frame and, covering said side openings, and means for retaining said panels and said bottom on said frame work. 80

3. A reflecting lighting fixture of the character described embodying an open top frame work comprising side walls having a plurality of openings therein and, having transversely extending supporting means adjacent the base, said base having an opening therein, a covering for said base opening supported by said transverse means, said covering including translucent material, other translucent material carried by the 90 sides of said frame work and covering the openings therein, and means for retaining said base covering and said side covering on said frame work. 85

4. A reflecting lighting fixture of the 95 character described embodying an open top frame work comprising sides having a plurality of openings therein and thereabout and a transversely extending bottom flange providing a bottom opening for the frame, a 100 covering for said bottom opening resting upon said flange, said covering including translucent material, a plurality of separate panels of translucent material carried by the sides of said frame work, and means for 105 holding said panels to said frame work.

5. A reflecting lighting fixture of the character described embodying an open top frame work comprising sides having a transverse flange adjacent the base thereof and 110 having apertures therein and thereabout, said flange providing a bottom opening for the frame, a covering for said bottom opening supported by said flange and composed, at least in part, of translucent material, a 115 plurality of separate panels of translucent material seated over said bottom covering and covering the apertures in the sides of said frame, and means for detachably holding said panels to said frame sides. 120

6. A reflecting lighting fixture of the character described embodying an open top frame work comprising upper and lower bands and a plurality of transverse connecting strips therebetween providing a 125 series of openings in the sides of the frame, the lower of said bands being provided adjacent its bottom edge with a transversely

extending flange providing a bottom opening for the frame within said flange, a bottom covering composed, at least in part, of translucent material seated over said flange, a plurality of separate panels of translucent material seated over said bottom covering adjacent its edges and covering the openings between transverse strips of the sides of the

frame, said transverse strips being provided with means for spacing said panels, and means for holding said panels against said bands and connecting strips.
